UNITED STATES PATENT OFFICE.

ALBERT N. BENDER, OF MILWAUKEE, WISCONSIN, ASSIGNOR OF TWO-THIRDS TO FRED G. HENSLER AND RICHARD H. McMAHON, OF MILWAUKEE, WISCONSIN.

CALF-WEANING DEVICE.

SPECIFICATION forming part of Letters Patent No. 731,424, dated June 23, 1903.

Application filed September 20, 1901. Serial No. 75,840. (No model.)

To all whom it may concern:

Be it known that I, ALBERT N. BENDER, a citizen of the United States, and a resident of Milwaukee, in the county of Milwaukee and State of Wisconsin, have invented certain new and useful Improvements in Calf-Weaning Devices; and I do hereby declare that the following is a full, clear, and exact description thereof.

10 My invention relates to devices for preventing calves from sucking at the udders of their mothers; and it consists in certain peculiarities of construction and combination of parts, as will be fully set forth hereinafter in connection with the accompanying drawings and subsequently claimed.

In the said drawings, Figure 1 is a plan view of my said device, partly broken away to better illustrate certain details of construction. 20 Fig. 2 is an edge view, partly in section, on the line 2 2 of Fig. 1.

Referring to the drawings, *a* represents the main portion or shield of my device, which is preferably of a generally rounded contour, 25 with horizontal upper end, centrally cut out, as indicated at *b*, and the two parts of the upper edge thus left each formed with a groove *c* therein, in which grooves are seated two pins *d e*. The pin *d* is designed to be permanently secured in place by the screw *f*, while the pin *e* is intended to be removable, but held in place in use by screw *g*. A strap *h*, preferably of metal, surrounds the pin *e*, the ends of this strap lapping the sides of the shield *a* and being secured thereto, as by rivets *i i*, the said strap being further formed with a slot *j* therethrough for the passage of the screw *g*. The shield *a* and the pins *d e* are preferably of wood, and the metallic strap *h* serves as an aid in the adjustment and support of the removable pin *e*.

In practice the screw *g* is removed and the pin *e* slipped outwardly, and then the device is applied to a calf, with the pin *d* thrust into the animal's nostrils on one side up to the cartilage therein, and then the pin *e* is pushed back in the other nostril to a like distance and secured by the screw *g*. In this arrangement the shield *a* will effectually guard against the calf sucking, but will not in any way pain or injure the animal.

As a matter of economy and convenience in manufacture I prefer to make the device, as herein shown and illustrated, with the two separate pins; but as it is only necessary that one pin or projection should be removable the projection *d* may be formed integrally with the shield, if desired in any instance, and the details of construction may be otherwise varied within the scope of my claims without departing from the spirit of my invention.

Heretofore calf-weaning devices have been constructed embodying sheet-iron frames, some with spike-guarded dishes fitting over the nose of the calf and others with spring-controlled rock-shafts carrying strands of barbed wire, these being designed to irritate either the calf or cow, and hence are objectionable from the consequent liability of injuring the animals, and such I neither claim nor use. Others have metallic frames bolted or riveted to boards or plates and provided with spring-catches and other operating mechanism; but these various devices are all of them heavy and clumsy, and my device is light, simple, and inexpensive, and yet equally efficient as those of the nature described, while free from the objectionable features just enumerated.

Having thus described my invention, what I claim as new, and desire to secure by Letters Patent, is—

1. A calf-weaning device, comprising a rigid shield having a central opening in the upper edge thereof, said edge being grooved on each side of the said opening, in combination with a pair of inwardly-projecting pins located in said grooves, and secured in place by screws, extending through said pins into said shield. 85

2. A calf-weaning device, comprising a rigid shield having a central opening in the upper edge thereof, in combination with a pair of projections extending toward each other across said opening and one of the projections being removable; a slotted strap around the removable projection forming a guide therefor in its adjustment, and having arms secured to the shield, and a securing-screw passed through the strap-slot and removable projection into the said shield. 95

3. A calf-weaning device, comprising a rigid

shield of uniform thickness throughout, and having a central opening in the upper edge thereof, said upper edge, on each side of said opening, having an open semicircular groove 5 therein; a pair of cylindrical pins, of less diameter than the thickness of said shield, seated in said grooves, and projecting partly across said opening, and the walls of said grooves extending to only half the diameters 10 of said pins; and a pair of screws extending

through said pins and into said shield through the bottom walls of said grooves.

In testimony that I claim the foregoing I have hereunto set my hand, at Milwaukee, in the county of Milwaukee and State of Wisconsin, in the presence of two witnesses.

ALBERT N. BENDER.
